UNITED STATES PATENT OFFICE

WILLIAM S. GUBELMANN, OF BUFFALO, NEW YORK

REPEATING MECHANISM FOR CALCULATING AND LIKE MACHINES

Original application filed January 10, 1900, Serial No. 1,004. Divided and this application filed August 10, 1918. Serial No. 249,303.

This application relates particularly to repeating mechanism for calculating and like machines, and is a division of my pending application Serial No. 1,004, filed January 10, 1900, and eventuating in Patent No. 1,429,201, granted September 12, 1922.

One of the objects of the invention is to provide improved means for adding the same amount on a set of accumulators at each 10 of a plurality of operations of the machine and with a single setting of the keys.

Another object is to provide means for adding the same amounts on a plurality of independent sets of accumulators at each of a 15 plurality of operations of the machine and with a single setting of the amounts by the controlling keys.

Another object is to provide means for causing printing mechanism to print the 20 same item or items at each of a plurality of operations of the machine and with a single setting of the item or items by the controlling keys.

Another object is to provide means for adding the same amount on one set of accumulators at each of a plurality of operations of the machine while adding different amounts 25 on another set of accumulators at each of said operations of said machine.

Another object is to provide key mechanism 30 for controlling all of the above results.

Another object is to combine the repeat key with total taking mechanism in such manner that the operation of the repeat key 35 will automatically render the total taking mechanism incapable of releasing the number keys from their detaining mechanism.

Other objects will be pointed out in the following description and claims.

I have shown a machine embodying repeating mechanism and non-printing mechanism, and the combinations of these two mechanisms have been claimed herein, as they 40 are useful in multiplying.

In the accompanying drawings consisting 45 of seven sheets:

Fig. 1 is a fragmentary top plan view of my improved adding and recording machine.

Fig. 2 is a vertical longitudinal section of 50 the same, taken substantially in line 2-2,

Figure 1, and showing the adding and recording mechanism of one column or set of keys in the normal or inoperative position.

Fig. 3 is a fragmentary perspective view of the units gear segment and controlling arm 55 of the main adding mechanism.

Fig. 4 is a perspective view of one of the registering keys.

Fig. 5 is a fragmentary perspective view showing the key lever, the main gear segment, the controlling arm and the printing segment of one of the higher columns of numbers.

Fig. 6 is a fragmentary longitudinal sectional elevation taken substantially in line 65 6-6, Figure 1, and showing the auxiliary adding and printing mechanism.

Fig. 7 is a fragmentary longitudinal sectional elevation taken substantially in line 70 7-7, Figure 1, and showing the mechanism whereby words are printed.

Fig. 8 is a longitudinal sectional elevation, taken substantially in line 8-8, Figure 1, and showing particularly the mechanism 75 whereby different parts of the machine may be thrown into and out of gear.

Fig. 9 is a vertical section taken substantially in line 9-9, Figure 2.

Fig. 10 is a vertical transverse section taken 80 in line 10-10, Figure 2.

Fig. 11 is a fragmentary transverse sectional elevation taken in line 11-11, Figure 2, and showing the mechanism for holding the keys in their depressed position and for releasing the same.

Fig. 12 is a fragmentary perspective view of the key holding and releasing mechanism.

Fig. 13 is a fragmentary transverse sectional elevation, taken in line 13-13, Figure 2.

Fig. 14 is a similar view showing one of the keys locked in a depressed position.

Fig. 15 is a fragmentary vertical section in line 15-15, Figure 11.

Figs. 16, 17, and 18 are views of details.

Like letters of reference refer to like parts in the several figures.

General construction

1 represents the main frame of the machine 100

which may be of any suitable construction so as to support the working parts of the machine.

2, Figure 2, represents a number of main dials which register the total of the numbers which are added together. These dials consist preferably of cup-shaped wheels which are numbered on their periphery and are mounted in their proper order on a transverse dial shaft 3, which is journaled in bearings on the main frame, the dials being so arranged that the dial representing the lowest number is arranged on the right hand end of the series and the dials representing the successively higher numbers being arranged successively in their order toward the left from the dial representing the lowest number. The lowest or right hand dial is preferably divided on its periphery into eighths so as to indicate fractions of a cent in eighths, and the remaining dials are graduated on their periphery according to the decimal system into tenths. As shown in the drawings ten total dials are shown and extend from fractions of a cent to tens of millions, but if desired, additional dials may be added to the right and to the left of the series, if it is desired to register smaller divisions of a cent or more than tens of millions. Each of the main total dials 2 is provided on its left hand side with a gear pinion 4, which is rigidly connected therewith, as shown in Figures 2 and 6. The pinion of the fraction wheel has eight teeth while the pinions of the remaining dials are each provided with ten teeth. 5 represents the main registering gear segments, one of which is provided for each of the dials 2 and is adapted to engage with the pinion thereof, for operating the respective dial. Each of these gear segments is arranged in rear of its companion gear pinion and is provided at its lower end with a rearwardly projecting arm 6 which is pivoted loosely on a transverse supporting rod 7. 45 This rod is mounted with its ends on the upper ends of two rock arms 8 which turn loosely with their lower ends on a transverse rock-shaft 9. The rock-arms 8 are connected by a transverse bar 10 which compels the two arms to move back and forth together. In the normal position of the gear segments when the machine is at rest these segments are retracted rearwardly out of engagement with the dial pinions of the dials and the segments are elevated so that their lowermost teeth are opposite the spaces between the adjacent teeth of the dial pinions, these spaces being in line with the pivots of the pinions and the gear segments.

60 The gear segments are yieldingly held backwardly out of engagement with the dial pinions by means of springs 11 connecting the rock-arms 8 with a stationary part of the frame. Figure 8 shows one of the springs 11 connecting one of the rock-arms 8 with a

transverse stationary bar 12 in the rear part of the machine. The gear segments are moved forwardly so that their teeth engage with the dial pinions 4 by means of a shifting rock-arm 13, which is preferably secured to the right hand rock-arm 8 and projects rearwardly. Upon raising the shifting rock-arm 13, the rock-arms 8 are swung forwardly and the gear segments 5 are engaged with the dial pinions, while upon swinging the shifting rock-arm downwardly, the rock-arms 8 are swung rearwardly and the gear segments are disengaged from the dial pinions.

14 represents a cam whereby the gear segments are engaged with the dial pinions. This cam is mounted on the upper portion of a vertically swinging rocking frame 15 which is arranged on the right-hand side of the machine. This cam is provided at its front end with an incline or cam face 16 and at its rear end with a concentric face 17. When the cam is in its rearmost or retracted position, its incline stands in rear of a roller or projection 18 on the rear end of the shifting arm 13, as shown in Figures 2, 6 and 9. Upon swinging the rocking frame 15 so that the cam 14 moves forwardly, the incline of the latter engages underneath the roller 18 and raises the arm 13, thereby moving the arms 8 forwardly. The throw of the incline 16 is just sufficient to engage the teeth of the gear segments with the dial pinions. When the roller 18 has been raised to the top of the incline, the concentric portion of the cam engages with the roller during the continued forward movement of the cam and the latter does not shift the gear segments any further forward.

When the rear end of the concentric face 17 of the cam passes forwardly from underneath the roller 18, the constant pull of the springs 11 causes the rock-arm 13 to be depressed and the rock-arms 8 to be moved rearwardly, thereby disengaging the gear segments from the dial pinions. Upon now moving the cam 14 backwardly together with the rocking frame 15, this cam does not affect the arm 13 and the parts connected therewith but is affected by said arm at the last portion of the backward movement of the cam, at which time the back or lower side of incline 16 engages with the roller 18 which lifts said incline and at the end of the backward movement of the cam, the latter clears said roller and drops behind the same, as shown in Figure 2, preparatory to again raising the roller 18 and connecting parts during the next forward movement of the cam 14.

For the purpose of permitting the front end of the cam to rise so as to clear the roller 18, this cam is pivoted at its rear end to the rear portion of the rocking frame 15. The upward and downward movement of the front end of the cam is limited by means of a lug 19 projecting from the side of the cam and engaging with a slot in the adjacent part of the rock-

ing frame 15, as shown in Figure 9. The rocking frame 15 is secured with its lower portion to a transverse rock-shaft 20 journaled in the main frame and provided outside of the frame with a hand crank 21, as shown in Figure 9, whereby this shaft is rocked and the parts connected therewith are operated.

The gear segments 5 are raised to their highest position by means of a return or lifting bar 22 which extends transversely underneath all of the arms 6 of the gear segments and which is connected loosely at its rear ends with the transverse rod 7 by lifting plates 23. 24 represents two shifting arms 15 which are mounted loosely at their rear ends on the rock-shaft 20 and which support at their other ends a transverse bar 25 which transverse bar is connected at its ends by two links 26, with the lifting plates 23, where- 20 by upon raising the shifting arms 24, the lifting bar 22 is caused to raise the gear seg- 25 ments and the other parts connected therewith resting on said bar. Upon depressing the transverse bar 25, the lifting bar 22 is moved downwardly and the gear segments resting thereon are permitted to move down- 30 wardly with the bar until the segments are arrested.

Each of the gear segments is yieldingly 35 held in contact with the lifting bar 22 by a spring 27 which connects the arm of the segment with the transverse bar 25. If the downward movement of the gear segment is arrested while the shifting arms 24 continue to move downwardly, the lifting bar 22 is moved away from the underside of the arm of the gear segment and the spring 27 is strained. The transverse bar 25 is arranged at one 40 front part of the rocking frame 15, shown in Figures 2, 6 and 9 and its opposite end is arranged in a similar segmental notch 28, formed in a rocking frame 29 which is secured to the operating shaft 20 on the left- 45 hand side of the machine. The rocking frames 15 and 29 together with the operating shaft 20 constitute the main or universal operating frame of the machine.

When the machine is at rest, as shown in 50 Figure 2, the transverse bar 25 engages with the front side of the notches 28 in the rock- 55 ing frames 15 and 29. Upon turning the rock-shaft 20 forwardly, by means of its handle 21, in the direction of the arrow, Figure 2, the rocking frames are moved forwardly during the first part of the movement independent of the transverse bar 25. The latter remains at rest until the inclined 60 front end 16 of the cam 14 has raised the arm 13 and moved the gear segments into engagement with the dial pinions, during which movement the rocking frames move idly the extent of their notches 28, along the ends of the bar 25 without disturbing the latter. After the gear segments have been

engaged with the dial pinions, the continued forward movement of the rocking frames causes the rear ends of their notches 28 to engage with the bar 25 and depress the same, thereby causing the lifting bar 22 to be moved downwardly and strain the springs 27. This causes all of the gear segments which are free, to be moved downwardly and to continue their downward movement until they are arrested. During the downward movement of the gear segments, while they are in engagement with the dial pinions, the latter and the dials connected therewith are turned until the downward movement of the segments is arrested. The extent which each dial is turned depends upon the position in which the downward movement of its operating segment is arrested. After the segments have been arrested in their downward movement, they remain in this position while the rocking frames complete their forward movement. At the end of the forward movement of the rocking frames, the roller 18 of the rock arm 13 drops off from the rear end of the concentric part of the cam 14, thereby allowing the springs 11 to pull the gear segments rearwardly out of engagement from the dial pinions.

Upon now turning the rock-shaft 20 backwardly by means of the handle 21, the rocking frames are moved backwardly, until the front ends of the notches engage with bar 25. When the latter is so engaged it is moved backwardly with the rocking frames to the end of their rearward movement which causes the transverse bar 25 to lift the lifting bar 22 and the gear segments which have been depressed into their highest or normal position. During this upward movement of the depressed gear segments they are out of engagement with the dial pinions, so that the dials are not turned backwardly with the segments, but remain in their shifted position. 30 represents a number of elbow-shaped controlling arms, which form part of the devices whereby the downward movement of the registering gear segments is controlled. One of these arms is arranged along the left-hand side of each gear segment and consists of an upright front part and a horizontal lower part which extends rearwardly from the lower end of the upright part, thereby leaving a clear space in rear of the upright part of the controlling lever as represented in Figures 1, 2, 3, 5 and 6. The rear end of the lower part of each controlling arm is mounted loosely on a transverse supporting bar 31, while the upper end of its front or upright part is loosely connected with the upper portion of its companion gear segment. This loose connection permits the controlling arm and the gear segment to swing freely about their individual axes, which are arranged parallel but out of line, and also permits the gear segment to move forward

and backward into and out of engagement with its companion dial pinion. In the uppermost position of the controlling arms the same bear with their upper ends against a transverse stop bar 32, as shown in Figure 2, which limits the upward movement of these arms. Each controlling arm is provided on the rear part of its upper end with a locking lug 33, and on the front part of its upper end with a stop lug 34, both of which 10 lugs project toward the left and are preferably stamped out in one piece with the controlling arm.

The operation of the registering devices 15 is controlled by a number of elbow-shaped key levers which are arranged side by side and pivoted to a transverse supporting rod 35. Each key lever is provided with a lower actuating arm 36, which projects forwardly, and an upper stop arm 37 which projects upwardly along the left hand side of one of the controlling arms and gear segments, as 20 represented in Figures 2 and 5. Each of these key levers is provided on the rear side 25 of its stop arm with a locking shoulder 38 which is adapted to engage with the locking lug 33 of the controlling arm when the latter is elevated into its highest position and the key-lever is in its fully retracted position, as 30 shown in Figure 2. When the parts are in this position, the key lever holds the controlling arm against downward movement and the latter holds the gear segment against downward movement. If the gear segment 35 while so held against downward movement is moved forward into engagement with the adjacent dial pinion, and the rocking frames are turned forwardly for depressing the gear segment, the spring 27 of this segment will 40 be strained without, however, shifting the segment. At the end of this forward movement of the rocking segments, the roller 18 of the rock arm 13 drops off from the rear end of the cam 14, the gear segment is moved 45 rearwardly out of engagement from the dial pinion and then the rocking frames move backwardly without having shifted the dial.

The upper arm of each key lever is provided on its front side with a vertical series 50 of differential stop shoulders 39, which are arranged step fashion and extend from the upper end of this arm downwardly and forwardly thereon, or in other words the stop shoulders 39 are arranged radially out of 55 line with one another and different distances from the pivot of the key lever. These stop shoulders of the key lever are adapted to be moved forwardly into the path of the stop lug 34 on the controlling arm. The stop 60 shoulders are arranged different distances from the stop lug 34 of the controlling arm, so that by moving different stop shoulders of the key lever into the path of the stop lug of the controller arm, the latter and the 65 gear segment connected therewith may be

arrested at different points in their downward movement. The uppermost stop shoulder of the key lever is most remote from the stop lug of the controlling arm and therefore requires the greatest forward movement of the key lever, in order to bring this stop shoulder into the path of this stop lug. 70

The stop shoulders of the key lever are so arranged that the distance from the stop shoulders to the path of the stop lug gradually grows less from the uppermost stop shoulder to the lowermost stop shoulder. The relative position of the different stop shoulders of the key lever is such that when its locking shoulder 38 remains in engagement with the locking lug 33 and the gear segment is simply moved into and out of engagement with its dial pinion, the latter remains at zero, if the same has not been previously moved. But when the key lever has been moved forwardly, so as to disengage its locking shoulder from the locking lug and moves one of its stop shoulders into the path of the stop lug of the controlling arm, the latter arm and gear segment connected therewith will be moved downwardly upon moving the rocking frames forwardly, until the stop lug of the controlling arm strikes the respective stop shoulder of the key lever which stands in its path, whereby the gear segment while turning in engagement with the adjacent dial gear pinion turns the same forward. By turning the key lever forward more or less and moving one or the other of its stop shoulders into the path of the stop lug 34 of the controlling arm, the distance which this arm descends can be varied, thereby varying the number of spaces which its gear segment turns the adjacent dial. 80 85 90 95 100 105

Main number key mechanism

40 represents the main keys whereby the key levers of the main registering and recording mechanism are operated, and which are guided with their depending stems in the top 41 and bottom 42 of the key-board. As shown in the drawings, nine longitudinal columns of these keys are arranged transversely side by side. The first column on the right-hand side of the machine contains seven 110 keys and represents fractions of one-eighth of a cent, the next column toward the left contains nine keys and represents cents and the remaining columns of keys toward the left each contains nine keys and represents progressively higher orders of numbers according to the decimal system, so that the registering keys in the last or left hand column represent hundreds of thousands of dollars. 115 120 125

The lowest numbers of the several columns of keys are arranged transversely in a row on the rear part of the key-board and the corresponding higher numbers of the several columns are arranged likewise in transverse 130

rows and progressively in their order toward the front end of the key-board.

Each of the registering keys is yieldingly held in an elevated position by a spring 43 (Figs. 11 and 13) surrounding the stem of the key and connected at its upper end to the key and bearing with its lower end against the bottom of the key-board. The upward movement of each key is limited by a shoulder 44 formed on the upper part of its stem and engaging with the underside of the top of the keyboard.

The downward movement of all of the keys is substantially the same, but the arrangement of each column of keys lengthwise of the lower actuating arm of each key lever causes the keys to bear against their lever at different distances from its pivot, so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted into the path of the stop lug 34 of the respective controlling arms. The throw of each key lever upon depressing any one of its keys is such that the proper stop shoulder on its upper arm is moved into the path of the stop lug 34 of the controlling arm, and the downward movement of the respective gear segment is arrested after having turned the adjacent dial gear pinion a number of spaces corresponding to the number of the key which is depressed.

Loose connection for segments

The loose connection between each controlling arm and its gear segment, heretofore referred to, is shown in its simplest form in the connection between the controlling arm and the gear segment, which are controlled by the initial or lowest column of registering keys. As shown in Figures 1 and 3, the loose connection between the controlling arm and the gear segment of the lowest registering device consists of upper and lower guide lugs 45 and 46 arranged on the upper end of the segment and bearing against the upper and lower guide faces 47 and 48, which are formed on the upper end of its companion controlling arm. As the controlling arm and segment rise and fall, the guide lugs of the segment slide back and forth on the guide faces of the arm. The guide faces are so constructed that the back and forth movement of the segment on the arm is radially with reference to the dial pinion in all positions of the segment. By so forming the guide faces of the arm, the gear segment can be engaged with and disengaged from the dial pinion in all positions of the segment without disturbing the position of the dial pinion. The construction of the loose con-

nnections between the controlling arms and gear segments of all of the higher registering devices above the fractional registering device are combined with carrying devices, whereby each registering dial, upon making one complete turn, causes the next higher dial to be turned forward one space, thereby carrying up a number from one column to the next higher column. The loose connections between the controlling arms and the segments and the carrying mechanism of the higher registering devices are constructed as follows:—

As shown in Figures 1, and 2, each controlling arm is provided at its upper end with upper and lower guide faces 47 and 48 and its lower guide face is engaged by a lower guide lug 46 on the adjacent gear segment, the same as in the coupling between the controlling arm and segment of the initial registering device. The gear segments of the higher registering devices are each provided with an upper guide lug 49 which is adapted at times to bear against the upper guide face 47 of the companion controlling arm in substantially the same manner in which the upper guide lug 45 of the fractional gear segment bears against its companion arm, the only difference being that the upper guide lugs 49 of the higher gear segments are held out of engagement and separated by a space from the upper guide face of the companion arm when no number is carried from a lower to a higher registering device. The upper guide lug 49 is held in this elevated position above the adjacent guide face by a rocking latch 50 which is arranged in a notch in the rear side of the gear segment and which normally projects toward the left and engages with the upper guide face 47 of the adjacent controlling arm, as shown in Figures 2 and 5.

During the ordinary up and down movement of each higher controlling arm and gear segment, the latter is guided by its lower guide lug 46 and the locking latch 50 engaging with the lower and upper faces of the adjacent arm, this movement being the same as the movement of the controlling arm and gear segment of the fractional registering device. Normally the downward movement of the controlling arm is determined by the position of its companion key lever and this arm in turn controls the extent of the downward movement of the gear segment. When, however, the locking finger 50 is withdrawn out of engagement from the upper guide face 47 of the arm, the companion gear segment is capable of moving downward independent of the arm until the upper guide lug 49 engages with the upper guide face of the arm. The extent of this independent movement of the gear segment with reference to its companion arm is equal to one tooth or space of the segment, so that by this means the gear segment is enabled to turn the dial pinion one space

more than the position of the key lever permits the same to move.

The withdrawal of the locking latch of each higher registering device is controlled by the next lower registering device and the withdrawal of each latch is effected when the next lower registering device has made one complete turn and arrived at zero. Each of the locking latches is pivoted on the right hand side of its adjacent gear segment, so as to turn transversely with reference to the latter. The latch is turned toward the left into its operative position by a spring 51, the movement in this direction being limited by a shoulder 52 arranged on the latch and bearing against the right hand side of the gear segment. 53 (Fig. 5) is an upright trip plate connected with the lower end of each latch and arranged normally at right angles or nearly so to the adjacent gear segment, when the latch is in its operating position. 54 represents a number of upright trip arms, each of which is controlled by a lower registering device and which turns the locking latch of the next higher registering device into an inoperative position. This arm is mounted loosely with its lower end on the supporting bar 35 and is provided at its upper end with a rearwardly and then forwardly projecting hook 55, and in front and below said hook with a bend forming a bearing finger 56 (Fig. 16). 57 represents trip cams arranged on the left-hand side of each registering dial pinion and connected with the adjacent pinion and dial, but separated from the pinion by an intervening space or groove. The face of each of these cams may begin at its lowermost point near the axis thereof and then extend outwardly in a spiral line terminating with its highest point in line with its lowermost point with which it connects radially and abruptly. The trip cam of the fractional registering device has its face divided into eight parts, each part of which except the first is arranged one-eighth of a space further from the center of the cam than the preceding part, while the trip cams of the higher registering devices each has its face divided into ten parts, each part except the first being arranged one tenth of a space farther from the axis of the cam than the preceding part. Each of the trip arms 54 extends upwardly along the right-hand side of the trip cam of a lower registering device, and its shoulder 56 engages with the face of this cam, while the hook 55 at its upper end extends toward the left and is adapted to engage with the trip plate 53 of the next higher registering mechanism. In the initial position of each trip arm, its shoulder 56 engages with the lowest part of its trip cam, as represented in Figures 2 and 6. As the trip cam is turned in the direction of the arrow, Figure 2, at the same time that the dial and gear pinion are moved forwardly, by the adjacent gear seg-

ment, during the adding operation, the trip arm is moved backwardly by the gradually rising face of the trip cam. During this backward movement of the trip arm, its hook engages with the trip plate 53 of the next higher registering device and is deflected toward the right thereby, the hook being sufficiently elastic for this purpose. After the hook has passed in rear of said trip plate, the hook owing to its resilience springs back to its normal position, so as to stand behind said trip plate. When the shoulder of the trip arm reaches the highest part of the face on the trip cam the trip arm has been shifted to its rearmost position. Upon now turning this cam forwardly another space together with its companion dial and pinion, the highest part of the cam is carried from underneath the shoulder of the trip arm and the latter is moved forwardly over the abrupt face of the cam until its shoulder 56 again engages with the lowest part of the cam face. During this movement of the trip arm, its hook strikes the rear side of the trip plate 53 of the next higher registering mechanism and turns the same forwardly, thereby disengaging the locking latch from the adjacent controlling arm and permitting the gear segment carrying the trip plate to move forward one space. The forward movement of the trip arm is effected when the dial with which its trip cam is connected has made one complete rotation and again stands at zero, whereby the addition represented by this complete rotation is carried to the next higher registering device. The forward movement of the trip arm is effected quickly by a spring 58, which connects with a stationary cross bar 59 arranged in front of the trip arms. The trip plate 53 of each registering device is so arranged and is of such length that the hook of the next lower trip arm can engage with the rear side of the plate, for disengaging its latch in any position of the gear segment carrying the plate, and in order to accomplish this engagement it is obvious that cams 57 should be constructed so as to give arms 56 the proper throw. If a gear segment is locked in its highest position by reason of none of its companion keys having been depressed, the withdrawal of its latch from the controlling arm simply permits the gear segment to drop one space and turn its companion dial pinion forward one space, while in engagement therewith, the movement of this dial representing one number carried up from the next lower dial. If any one of the keys of the key levers has been depressed, so as to release the gear segment and permit the same to move downwardly for effecting an addition, and if during this time the next lower registering device has made a complete turn, so as to require the carrying up of a number from the next lower registering mechanism, the latch of the higher registering

device will be withdrawn while the same is effecting its addition, thereby causing the segment to descend and turn its dial one space in addition to the spaces corresponding to the depression of its respective key.

- 5 When the locking latch has been withdrawn so as to permit a gear segment to move downwardly one space farther than its controlling arm, the latch remains in this position during the subsequent upward movement of the arm and the segment until the upward movement of the arm is arrested by striking the stop bar 32, and the gear segment continues its upward movement independent of the arm the extent of one space.
- 10 The gear segment has now reached its highest position, and its latch is again swung automatically, by its spring, over the controlling arm. The controlling arm and gear segment now remain in this relative position until another number is to be carried up from the next lower registering device.
- 15

When the controlling arm has been retracted to its highest position, the adjacent key lever is moved into its normal retracted position, so that its locking shoulder 38 engages with the locking lug 33 of the controlling arm and locks the latter against downward movement. The return movement of each 25 key lever is preferably effected by a spring 60 which connects the upper arm of the key lever with the transverse shaft 9, as shown in Figure 2, or with some other convenient part of the machine. The lower guide lug 35 of the gear segment is not absolutely necessary because the weight of the parts connected with the controlling arm and arranged in rear of its pivot is sufficient to raise the arm, but it is preferable to employ 30 this lower guide lug 46 on the gear segment because it compels the arm to rise with the gear segment and avoids displacement of these parts with reference to each other, and also serves as a stop to limit the upward 35 movement of the gear segment.

The gear pinion and the co-operating gear segment of the fractional registering device are so constructed that the fractional dial makes one rotation whenever it is moved 40 forward eight spaces. After the fractional dial has made one rotation the whole number represented by this rotation is transferred by the first carrying device from the registering mechanism of the fractional dials to the next higher registering device which represents cents. The complete turns of each 45 of the following registering devices are in like manner carried or transferred to the next 50 higher dial by the respective carrying device. The dial which records the highest number, in this instance the millions of dollars is preferably operated only by the adjacent carrying device of the next lower dial and is incapable of being operated directly from

the key-board because it is not provided with a key operating mechanism.

The mechanism whereby the dials are all turned back to zero or the place of beginning after the addition of numbers has been completed is constructed as follows:

61 represents a series of feeling rock levers which are adapted to shift the key levers, so as to permit the gear segments to descend the proper distance for resetting or restoring the main registering dials to zero. One of these shifting levers is mounted loosely on the supporting bar 35 adjacent to the left hand side of each of the key levers and is provided on its upper arm with a forwardly 75 projecting feeling finger 62 and with a shifting finger 63 which extends behind the upper arm of the adjacent key lever. The feeling levers have their fingers arranged in rear of the total cams, 57, and each of these levers is turned so that its upper arm moves backwardly by the upper arm of the adjacent key lever engaging with the shifting finger 63 of the feeling lever. 64 represents a transverse pull bar arranged in rear of the lower 80 arms of the feeling levers and connected with each of the latter by a pull spring 65, as represented in Figures 2 and 6. This pull bar is connected at its ends to the lower ends of two depending pull or rock arms 66, which 85 are secured at their upper ends to the rock shaft 9, as shown in Figure 6. Upon turning this rock-shaft, so as to swing its depending pull arms backwardly the feeling levers are turned by means of the springs 65 so as to 90 move the upper arms of these levers forwardly. This movement of the rock-shaft 9 is effected by a cam 67, which is mounted on the left-hand side of the rocking frame 29 and which is constructed substantially the 95 same as the cam 14 which is mounted on the rocking frame 15. As shown in Figures 8 and 9, this cam is pivoted at its rear end by a transverse pin, to the rear portion of the rocking frame 29 and is provided at its 100 front end with an incline or cam face 68 and in rear of the incline with a concentric face 69. The cam 67 is pivotally supported on the rocking frame 29 in the same manner in which the like cam 14 is pivoted on its corresponding rocking frame 15. The cam 67 can be raised and lowered with its front end into an inoperative or operative position, this movement being limited by means of a lug 70 arranged on the cam, as shown in Figure 9, and projecting into a slot 71 (Fig. 8) in the adjacent rocking frame in the same manner in which the movement of the cam 14 is limited.

72, Figures 8 and 9, represents a rearwardly projecting rock-arm secured to the rock shaft 9 and provided at its rear end with a roller or projection 73 which is adapted to be engaged by the cam 67 for turning the rock shaft 9. When numbers are being added with the ma- 125 130

chine, the cam 14 is depressed, as shown in full lines, Figure 2, so as to be in a position when moved forwardly by the rocking frame 15 to engage the roller on the arm 13, for moving 5 the gear segments into engagement with the dial pinions, and during this time the cam 67 is lifted into the position shown in full lines, Figure 8, so that when the rocking frame 29 is moved forwardly, the cam 67 will clear the 10 roller 73 of the rock arm 72 and not disturb the rock-shaft 9 and the parts connected therewith.

If it is desired to restore all of the total 15 dials 2 to zero, the cam 14 is raised into its inoperative position, shown by dotted lines 14^a in Figure 2 and the cam 67 is lowered into its operative position, as shown by dotted lines 67^a in Figure 8. Upon now turning the rock-shaft 20 by hand so as to move both rocking 20 frames 15 and 29 forwardly, the cam 14 passes over the roller 18 of the arm 13 without disturbing the same, but the inclined front of the cam 67 engages with the roller 73 on the rear end of the rock-arm 72 and raises the same 25 until this roller engages with the concentric part 69 of this cam. By this movement of the arm 72, the rock shaft 9 is turned in the direction for moving its depending arms 66 rearwardly and pulling the springs 65 rearwardly. 30 This pull on the springs 65 causes the feeling levers to be turned until the feeling fingers of their upper arms engage with the spiral surfaces of the trip cams. After the feeling fingers bear against these cams, their movement is arrested and the continued backward 35 movement of the pull-bar 64 simply stretches the springs 65 until the bar reaches the end of its backward movement. The feeling finger of each feeling lever engages with 40 that part of the surface of the adjacent trip cam which is directly opposite the feeling finger, and as these trip cams are turned with the adjacent dial they present different parts of their spiral surfaces to the opposing feeling fingers, which causes the forward movement 45 of the upper arms of the feeling levers to be arrested in different positions when swung forwardly. During the forward movement of the upper arm of each feeling 50 lever, its shifting finger 63 engages with the rear side of the upwardly projecting arm of the adjacent key lever and moves this arm forwardly. The construction of the parts in such that the spiral surfaces of the trip 55 cam bears a definite relation to the step-shaped series of stop shoulders on the upper arm of the key lever. When the feeling finger of the feeling lever, upon being moved forwardly, bears against the lowest key lever- 60 stop-controlling part of the adjacent trip cam, the adjacent key lever is carried simultaneously forward with the feeling lever the greatest distance and its uppermost stop shoulder is carried into the path of the stop 65 lug of the controlling arm. The succeeding

parts of the spiral surface of the trip cam are so constructed that they rise progressively higher and arrest the forward movement of the feeling lever when the same has carried the adjacent key lever with its corresponding stop shoulder into the path of the stop lug of the controlling arm. This forward movement of the feeling lever and that of the upper arm of the key lever is gradually reduced as the progressively higher parts of the trip cam are presented to the feeling finger, and when the highest part of the trip cam is presented to the feeling finger, the feeling lever is prevented from moving forward at all and the upper arm of the key lever is not moved with its locking shoulder out of engagement with the locking stop of the controlling arm and consequently the companion gear segment connected therewith is held against downward movement. After the rocking frames 15 and 29 have been turned forwardly sufficiently to engage the several feeling fingers of the feeling levers with their respective trip cams, the rear ends of the segmental notches 28 in the rocking frame engage with the cross bar 25 and depress the same, thereby moving the lifting bar 22 downwardly and at the same time pulling down the springs 27. This downward pull on these springs causes each spring to pull its respective gear segment down as far as possible, and after the downward movement of the segment has been arrested the continued downward movement of the cross bar 22, together with the rocking frames simply stretches these springs until this bar reaches the end of its downward movement. If a gear segment is locked in its uppermost or zero position, its spring 27 will be stretched its fullest extent, whereas, if a gear segment moves downwardly more or less before it is arrested by its shifted key lever, its spring 27 will be stretched less in proportion. This downward movement of the gear segments which are free to move in this direction takes place while the gear segments are in their retracted position and out of engagement from the dial pinions, so that the dials are not affected by this movement of the segments.

After the rocking frames have reached the end of their forward movement and the roller 73 has dropped off from the rear end of the concentric portion 69 of the cam 67, the gear segments are moved forwardly by hand operated mechanism into engagement with their respective dial pinions and are held in this position during the entire subsequent backward movement of the rocking frames, which is effected by hand operated mechanism. During the backward movement of the rocking frames, the gear segments are raised to their highest positions, while in engagement with the dial pinions by the rod 22 and connecting parts and turn the dials backwardly. At the end of the upward movement of the

gear segments the latter are released, so as to permit them to move into their retracted position, out of engagement from the dial pinions.

During this operation, those gear segments which are held or locked in their highest positions, by reasons of their dials being at zero, are simply moved forward at the end of the forward movement of the rocking frames, so as to engage with their respective dial pinions and are again moved backwardly out of engagement therefrom at the end of the forward movement of the rocking frames, without disturbing their respective dials. Each of the unlocked gear segments is moved downwardly a number of spaces corresponding to the number which is registered on its dial, the extent of this movement being controlled by the companion trip cam which arrests the forward movement of the key lever, through the medium of its feeling lever, when the proper stop shoulder of the key lever has been presented to the controlling arm.

Upon now moving the gear segments forwardly in their variously depressed positions and then raising them to their highest position, each depressed gear segment will turn its dial backward the same number of spaces that the gear segment was depressed. Inasmuch as each gear segment was permitted to descend by its trip cam, feeling lever and key lever the same number of spaces as the number indicated on its dial, the gear segment subsequently moves upwardly the same number of spaces before reaching its highest position, thereby turning its dial backwardly the same number of spaces and restoring the same to zero. When all of the dials have been returned to zero, the shoulders 56 of all the trip arms engage with the lowest parts of all the trip cams 57. The cams 14 and 67 are provided with a longitudinal slit 74, (Fig. 18) so as to facilitate the manufacture of these parts.

The mechanism whereby the positions of the cams 14 and 67 are reversed preparatory to restoring the dials to zero is constructed as follows:

The cams 14 and 67 drop into their operative position by gravity. Each of these cams is provided in rear of its pivot with a tail 75 (Fig. 8) which is depressed when it is desired to lift the respective cam into its inoperative position.

76 is a shifting lever which is pivoted at its lower end and is normally turned so that its upper end is disengaged from the rear side of the tail on the cam 14, by a spring 77, as shown in Figure 2. The member 76 projects in rear of the main frame so as to be accessible for manipulation. 78 is a shifting lever which is pivoted between its upper and lower arms and arranged with its upper arm in rear of the tail on the cam 67 and normally held in engagement therewith by a spring 79, as shown in Figure 8. 80 represents an elbow

lever pivoted below the bottom of the key-board, as represented in Figure 8. 81 represents a main line or cord which is connected with the lower arm of the elbow lever 80 and which is provided at its rear end with two branches 82 and 83. The branch 82 connects with the shifting lever 76 above its pivot, and the branch 83 connects with the shifting lever 78 below its pivot. 84 represents a total or shifting key having a depending stem which is guided in top and bottom of the key-board and which bears with its lower end against the upper arm of the elbow lever 80. Upon depressing the key 84, the elbow lever 80 is turned, so as to draw the cords or lines 81, 82 and 83 forwardly, thereby moving the upper end of the shifting lever 76 into engagement with the tail of the cam 14 and lifting the same into an inoperative position, while the shifting lever 78 is moved rearwardly with its upper arm from the tail of the cam 67, thereby allowing the latter to drop into its operative position. Upon depressing the gear segments while the parts are in this shifted position, the segments move downwardly out of engagement with the dial pinions. After the gear segments have been depressed, they are moved forwardly into engagement with their respective dial pinions by an elbow lever 85 which is connected with its lower arm by a line or cord 86 to the rod or bar 7, as shown in Figure 8, or to one of the rock arms 8. The elbow lever is turned in the proper direction for this purpose by a shifting key 87 having a depending stem which is guided in the top and bottom of the key-board and which bears against the upper arm of the elbow lever 85. After the gear segments have been moved forwardly into engagement with the dial pinions, while in the depressed position, the gear segments are retained in forward position, and at the same time raised until they reach their uppermost position, whereby the dials are turned to zero. The shifting key 87 is now released which permits the spring 11 to move the gear segments rearwardly out of engagement with the dial pinions. The key 84 is also released, thereby permitting the shifting levers 76 and 78 to resume the positions shown in Figures 2 and 8, leaving the machine in position to resume adding. Each of the dials is held against turning while its companion sub-total dial is being turned to zero by means of a detent pawl 103 which engage with the front side of its companion gear pinion, as shown in Figures 2 and 6. The pawls 103 of the several gear pinions are mounted on a transverse pawl bar 104, which is supported at its ends by means of two pawl arms 105, which turn loosely upon the supporting rod or bar 35 of the key levers. The pawl arms are moved rearwardly for engaging the pawls of the bar 104 with the gear pinions, by means of springs 106 (Fig. 8).

These springs are connected loosely at their rear ends to the rock-shaft 9 and at their front ends to the pawl arms 105. During the forward movement of the gear segments preparatory to turning the dial pinions, the detent pawls are swung forwardly out of engagement with the dial pinions by means of two shifting rods 107 which are connected at their rear ends to opposite ends of the transverse rod 7 or some part moving therewith and each of which is provided at its front end with a fork or bifurcation 108, which engages with a pin or shoulder 109 on the pawl arm arranged on the adjacent side of the machine. As the gear segments move forward into engagement with the gear pinions the shifting rods 107 move the detent pawls 103 out of engagement with the dial pinions, and when the gear segments move backwardly the detent pawls are again engaged with the dial pinions by the springs 106.

Recording mechanism

For the purpose of recording the numbers which are added together by the above described mechanism a recording mechanism is provided which is constructed as follows:—

140 represents a printing roller or platen which is arranged transversely in the upper, rear part of the machine and under the lower side of which the sheet or other article is placed which receives the record. 141 represents a number of type segments which are arranged transversely side by side below the platen and which are pivoted at their front ends to the supporting bar 31 upon which the rear ends of the controlling arms 30 are pivoted. Each of these type segments is provided at its rear end with a segmental row of type carriers 142, which are capable of moving radially back and forth on the type segment.

Each of the type carriers is provided at its rear end with a type and is guided upon the type segment by means of screws or rivets 143 secured to the type carrier and arranged in radial slots 144 formed in the type segment, as shown in Figures 5 and 17. Each of the type carriers is held in its inward or retracted position by means of an S-shaped spring 145, which is arranged between the carrier and the type segment and is secured with one end to the carrier and with its other end to the type segment. Upon raising or lowering the type segment, any one of its type can be brought to the printing point or line, and upon striking the back or inner end of the type carrier, when the same is in line with the printing point, the type carrier will be driven outwardly and its type will produce an impression on the sheet supported by the platen. After the carrier has received the blow for driving the same against the platen, the carrier is again quickly retracted to its innermost position by means of its spring.

Each of the type segments is connected with one of the controlling arms, so that upon depressing a controlling arm and the registering gear segment connected therewith, the companion type segment will be raised and present one of its type to the printing point. 70

For convenience in operating the machine, the keys are separated a considerable distance on the key-board and in order to produce a compact record, the printing segments 75 are arranged closer together than the keys and the registering mechanism. In order to permit of this arrangement, each type segment and its corresponding controlling arm are connected by a connecting arm 146, as represented in Figures 1, 2 and 5. The connecting arms of the central controlling arms and type segments are comparatively straight, but the connecting arms of the outer type segments and controlling arms are arranged obliquely, the degree of this obliquity gradually increasing from the central type segments 80 and controlling arms in opposite directions toward the outer type segments and controlling arms, as represented in Figure 1. The 90 connecting arms 146 of the outer controlling arms are arranged in the spaces behind the upright parts and above the horizontal parts of the controlling arms, thereby permitting the inner controlling arms to move up and 95 down without interfering with the connecting arms 146 of the outer controlling arms.

The types on each type segment are arranged to correspond with the teeth and numbers of its companion gear segment and 100 registering dial, the zero type being at the upper end of the series and the progressively higher digits arranged in their order downwardly from the zero type. When the registering gear segment is in its highest position, 105 it presents its zero tooth to the dial pinion, and the type segment which at this time is in its lowest position presents its zero type to the printing point. Upon depressing a gear segment so as to present one of its higher 110 teeth to the dial pinion, its companion type segment is raised proportionally and presents a corresponding higher numbered type to the printing point.

147 represents a number of hammers 115 whereby the type carriers are struck for driving the type against the platen. One of these hammers is arranged adjacent to each type segment and is provided with a head which is arranged in front of the series of types and 120 in line with the printing point of the platen. Upon shifting the type segment so as to bring one or another of its type carriers to the printing line and then operating the hammer, the latter delivers a blow against the inner end 125 of the particular carrier which is at the printing point and produces an impression of its type on the platen. The several hammers are pivoted on the transverse rod 12, arranged in rear of the segments; and each of the ham- 130

mers is yieldingly held in its forward position by a spring 148 connected at its lower end to a cross bar 149 and at its upper end to a depending arm 150 on the hammer.

5 While the drawings show a preferred means for operating said hammers, which means is fully described in the parent application, Serial No. 1,004, now Patent No. 1,429,201, any suitable means may be employed for this purpose and as the specific 10 hammer operating mechanism forms no part of the invention claimed in this application, this mechanism is not described in detail. It will be sufficient for the purposes of this application to state that the hammers are retracted from the types and then released by pawls 153, Figure 2, which pawls are mounted on and operable by a rod 151. The rod 151 is moved to operate the pawls, by means 15 of a hooked member 168, pivoted on the rod 151 and normally engaging the bar 169, which latter is operated at each operation of the rocking frames 15 and 29.

20 Suitable means are provided for automatically effecting printing of zeros in the items. Any suitable means for this purpose may be employed, that shown in the drawings being the preferred one which is fully described in the parent application, Serial No. 1,004, now 25 Patent No. 1,429,201, to which reference is hereby made.

Non-print mechanism

When it is desired to only add the numbers and not record the same, the coupling hook 168 (Figs. 2 and 8) is raised with its notch out of engagement with the cross bar 169, which allows the rocking frames and connecting parts to move back and forth 30 without affecting the hammer operating devices. The coupling hook is disengaged from the cross bar by means of an elbow 171 secured to a transverse rock shaft 172. The lower arm of the elbow lever is connected 35 with the shaft 20 by a spring 173, whereby the lever and the shaft carrying the same are turned in the direction for disconnecting the upper arm of the lever 171 from the hook 168 thereby permitting the latter to engage 40 the bar 169. 174 represents an elbow lever arranged below the bottom of the key-board and connected by a line or cord 175 with its lower arm to the upper arm of the elbow lever 45 171 as represented in Figure 8. 176 represents a shifting key having a depending stem which is guided in the top and bottom of the key-board and which engages with its lower end against the upper arm of the elbow lever 50 174. Upon depressing this key the elbow lever 174 is turned in the direction for moving the rock arm 171 into engagement with the coupling hook 168 and disengaging the latter from the cross bar 169, thereby throwing the recording mechanism out of gear. Upon 55 releasing the key 176, the rock arm 171 is per-

mitted to swing backwardly and allow the coupling hook to engage with the cross bar 169, thereby throwing the recording mechanism into gear. When the gear segments and the printing segments are thus operated relatively to the keys which have been depressed, the number represented by the depressed keys is registered and also recorded by the printing mechanism. The addition of further numbers proceeds in like manner the several 70 numbers added successively by the registering mechanism but each number is printed 75 individually by the recording mechanism.

When it is desired to print or record the total at the foot of the column of the numbers 80 which have been printed, the operation is as follows:—The total key 84 is first depressed, thereby raising the cam 14 into an inoperative position and lowering the cam 67 into an operative position. Upon now moving the 85 rocking frames 15 and 29 forwardly, the feeling levers 61 are turned so as to move their feeling fingers forwardly into engagement with the respective cams 57 and at the same 90 time each feeling lever carries the adjacent key lever forwardly so that its particular stop shoulder 39 corresponding to the position of the trip cam 57 and its dial is moved into the path of the stop lug 34 of the controlling arm. After the key levers have been 95 thus shifted forwardly into their respective positions corresponding with their dials, the continued forward movement of the rocking frames causes the gear segments while in a 100 retracted position out of engagement with the dial pinions to be depressed until each segment is arrested by the engagement of the stop lug on its controlling arm with the respective stop shoulder of its key lever; whereby each printing segment is raised so as to 105 present the type carrier to the printing point which carries the type corresponding to the number registered on its companion dial. During the last part of the forward and 110 downward rocking movement of the rocking frames the hammers are operated and the particular type at the printing line are impressed on the platen. Upon now swinging the rocking frames backward the gear segments are raised while still in a retracted 115 position out of engagement with their companion dial pinions, thereby permitting further numbers to be added to the total already registered on the dials. If, however, it is desired to turn the dials back to zero, after the 120 total of the added numbers has been printed or recorded the gear segments, while in the retracted lower position which they occupy while printing the totals, are moved forwardly into engagement with their respective dial pinions by the depression of the key 87. Upon now moving the rocking frames backwardly the gear segments are raised while in their 125 forward position in engagement with their pinions, whereby each of the latter is turned 130

backwardly and when the segments reach the end of their upward movement, the dials have been turned backwardly a number of spaces corresponding to the number on the dial, 5 thereby turning all of the dials to zero.

Word printing mechanism

For the purpose of permitting words to be printed in front of the numbers which are 10 added together the following mechanism is provided:—

1411 (Figs. 1, 7, 9 and 10), represents a word-printing segment which is mounted loosely on the rod 31 next to the highest number printing segment of the main number recording mechanism. This segment is provided with a number of radially movable carriers 1420, which are constructed the same as the carriers of the number printing segments and each of 15 which is provided on its face with a word-type. The words of these types are selected according to the purpose or business for which the machine is to be used. For instance, if the machine is to be used in a bank, 20 types representing the words "Vouchers", "Checks", "Drafts", "Bills", and similar words common to the banking business may be used. When the machine is designed for use in a restaurant the words "Soup", "Vege- 25 tables", "Meats", "Dessert", and other words 30 peculiar to this business may be used.

The position of the word type segment is controlled by a key lever 3600, Figure 7, which turns on the bar 35, is similar to the 35 number key levers and is provided on the front side of its upper arm 3700 with a vertical series of differential stops or shoulders 3900 which are adapted to be engaged by the stop lug 3400 of a controlling arm 3000; and 40 lever 3600 is also provided with a locking stop or shoulder which is adapted to be engaged by a locking lug 3300 on the controlling arm, as represented in Figure 7. The controlling arm 3000 is connected with the word printing 45 segment by a connecting bar 1460. The stop shoulders on the upper arm of the word key lever are so arranged that upon swinging this lever so as to carry different shoulders into the path of the stop lug on the controlling 50 arm, the latter will be arrested at different points in its downward or forward movement and the word printing segment connected therewith will be stopped at different points in its upward movement and present 55 the particular word type to the printing point which corresponds with the shoulder or stop on the word key lever. The upward movement of the controlling arm 3000 is limited by its rear locking lug 3300 engaging 60 with the stop bar 32 which arrests the upward movement of the controlling arms 30 of the number registering and recording mechanism. The downward movement of the controlling arm 3000 and the simultaneous up- 65 ward movement of the word printing segment

is effected by a spring 215 which yieldingly connects this arm with the bar 25 to which the registering gear segments are connected.

216, Fig. 1, represents a row of word keys having depending stems which are guided in 70 the top and bottom of the key-board and which engage against the upper side of the front arm 3600 of the word key lever at different distances from the fulcrum thereof. Upon depressing any of the word keys the 75 word key lever will be turned the proper distance to bring its proper stop shoulder into the path of the stop lug of the companion controlling arm and arrest the word type segment during its upward movement, when 80 the word type corresponding with the word of the depressed key has reached the printing line. When the respective word type is in this position the same is driven against the recording surface for producing an impression thereon, at the same time that the printing of the numbers by the numbering printing segments is effected. The word types are driven against the platen by a hammer operating mechanism which is constructed the same 85 as the hammer operating devices of the number printing mechanism and the same letters of reference are therefore used to denote the same. The word key lever is yieldingly held in its normal position by a spring 600. 90

Auxiliary adding mechanism

An auxiliary adding mechanism is provided which permits of registering and recording the individual or separate number of 100 adding and recording operations which have been made by the main adding mechanism and also permits of effecting an addition of numbers different from the numbers which are added by the main adding mechanism. 105

This auxiliary adding mechanism is constructed as follows:

2000 (Fig. 6) represents a number of auxiliary dials which are mounted on the left hand end of the dial shaft 3. 5000 represents 110 a number of auxiliary gear segments which are mounted on the transverse rod 7 and are adapted to engage with gear pinions 400 on the auxiliary dials. Each gear segment 5000 is connected with a controlling arm 3001 arranged adjacent to the gear segment by a latch or coupling which at times permits the segments to move independently of the controlling arm. 3601 and 3701 represent auxiliary key levers which are operated by auxiliary keys 401 (Fig. 1) and which control 115 the operation of the auxiliary registering and recording mechanism. The detail construction of the dials, gear segments, printing segments, key levers and the parts co-operating therewith of the auxiliary registering and recording mechanism is substantially 120 the same as the construction of the same parts in the main registering and recording mechanism, except as hereinafter distinguished, 125

and the same letters of reference are therefore employed to denote like parts in both of these sets of mechanisms.

In the drawings, two auxiliary key levers 5 and three auxiliary dials are shown, which permits of registering and recording a total of 999, but additional registering and recording devices may be employed if it is desired to increase the capacity of the machine.

10 In the auxiliary mechanism each of the higher gear segments 5000 is provided with a pivot latch identical in construction with the latches 50 in the main registering mechanism. The lowest or primary gear segment 15 of the auxiliary registering mechanism is provided with a movable latch 502 which is adapted to be engaged with or to be disengaged from the upper guide face on its companion controlling arm, but for the purpose 20 of the present application this latch might be dispensed with and the primary gear segment constructed the same as the primary gear segment of the main registering and recording device.

25 In the auxiliary registering mechanism the gear segments are not provided with lower stops 46 like those of the gear segments of the main registering mechanism, which permits the auxiliary controlling arms to move downwardly when necessary independently of the auxiliary gear segments. The upward movement of the auxiliary gear segments is limited by stops 218 with which the upper ends of the gear segments engage. 219 represents a 30 foot formed on the lower side of each controlling arm 3001 and adapted to engage with the lifting cross bar 22. However, for the purposes of the present application, the auxiliary mechanism could be made exactly as the 40 main number registering and recording mechanism is made.

For the purpose of effecting an ordinary addition of numbers on the auxiliary registering mechanism, the auxiliary key levers are 45 shifted into the proper position by the depression of the keys 401 representing the numbers to be added and then the rocking segments 15 and 29 are turned forwardly. During the forward movement of the rocking frames the auxiliary gear segments are first moved into engagement with the auxiliary dial pinions by the cam 14 and then pulled down by the springs 27, and the controlling arms are also pulled down by the latches of 50 the gear segments engaging with the controlling arms. The downward movement of the gear segments and controlling arms continues until the stops 34 of the controlling arms 55 strike the shoulders 39 on the key levers which stand in the path of the stops 34. At the end of the forward movement of the rocking frames the gear segments are withdrawn from the dial pinions by the springs 60 and during the subsequent backward movement of the rocking frames, the gear segments and

controlling arms are raised by the cross bar 22 engaging with the gear segments and with the feet 219 of the arms. The carrying of numbers from the units dial to the tens dial and from the latter to the hundreds dial and the turning of the dial to zero is effected in the same manner as in the main registering mechanism.

By this organization of the machine, numbers such as sales or prices of goods can be 70 added and recorded by the main registering mechanism, and other numbers such as the rebate on sales or discount on the prices of the goods, can be separately added and recorded by the auxiliary registering mechanism.

The key controlled devices whereby the parts of the main registering and recording mechanism are shifted into the proper position preparatory to registering and recording a number are distinct from the key controlled 80 devices whereby the same effect is produced in the auxiliary registering and recording mechanism, but both sets of registering and recording mechanisms are operated simultaneously by the one universal shifting mechanism for effecting the registration and recording of the numbers which are represented by the different positions of both key controlled devices.

Keyboard mechanism

The keys which have been depressed in the operation of adding or recording a number, word or other character are automatically locked in a depressed position until the adding or recording operation of the particular number, word or other character has been completed, and then the depressed keys are automatically released and permitted to be raised by their springs.

As shown in Figures 2, 6, 8, 11, 12, 13 and 14, the keys are held in a depressed position by a number of locking plates 327, one of which is arranged lengthwise on the left side of the stems of each row of keys. Each of the locking plates is pivoted at its lower end to the top of the keyboard bottom, so as to swing transversely and is provided along its upper edge with a number of downwardly facing catches or shoulders 328 which are adapted to engage with upwardly facing locking shoulders 329 on the stems of the keys. Each of the keys is provided with a convex face below its locking shoulder, consisting of a lower rising portion 330 which inclines upwardly and laterally from the lower part of the key toward the adjacent locking plate, and an upper receding portion 331 which inclines from the upper end of the rising portion to the outer end of the locking shoulder 329 of the stem, 110 as shown in Figures 12 and 13. Each locking plate is drawn yieldingly with its catches against the stems of the adjacent row of keys by a spring 332, as shown in Figure 13. The locking catches of the locking plates bear 115 against the key stems below the convex faces 120

125

130

thereof when the keys are in an elevated position, as shown in Figure 13.

Upon depressing a key the convex face on its stem deflects the locking plate and when the key has been depressed fully the respective locking catch of the locking plate engages with the locking shoulder 329 of the stem of the depressed key, thereby retaining the parts which are operated by said key in a shifted position. If a wrong key has been depressed and the operator subsequently depresses the right key the latter during the first part of its downward movement engages the lower or rising part 330 of its convex face with the adjacent locking catch of the locking plate and disengages the respective locking catch from the locking shoulder of the previously depressed key, thereby releasing the same. Upon continuing the depression of the second or correct key after the first or wrong key has been released, the receding or upper part 331 of the convex face of the correct key engages with the adjacent locking catch of the locking plate, thereby permitting the latter to approach the key stem and when the correct key has been fully depressed its locking shoulder is carried below the locking catch of the plate and is engaged thereby, whereby the correct key is locked in a depressed position, as represented in Figure 13. By this means any incorrectly depressed key is automatically released by the depression of the correct key and the latter is in turn automatically locked in a depressed position.

Automatic key release

333 (Figs. 6, 11 and 12) represents a transversely movable releasing bar, whereby the keys of the main number registering devices are released. This bar is arranged transversely in rear of the rear ends of the locking plates of the main number keys and is guided with its ends in the frame of the machine, as shown in Figures 11 and 15. This bar is provided with a number of upwardly projecting releasing lugs or shoulders 334, one of which is adapted to engage with the right side of a pin or projection 335, on the rear end of each locking plate of the main registering keys, as represented in Figure 11. Upon shifting the releasing bar 333 toward the left its releasing lugs move the main locking plates in the same direction, thereby releasing any number keys which are held in a depressed position by the same. The main releasing bar 333 when free is shifted toward the right into its retracted position by the resilience of the springs which hold the main locking plates in their operative position.

The releasing bar 333 is shifted into its operative position by a releasing elbow lever 336 which turns on a pivot pin 337 and is connected with its upwardly projecting arm 65 with the releasing bar 333 while its lower

arm projects horizontally outward. 338 represents a releasing arm which is arranged lengthwise in the machine and transversely over the lower arm of the releasing elbow lever 336 and which is pivoted at its front end on a pin 339, as represented in Figures 8, 11 and 12. 340 represents a longitudinal releasing lever connected by an upright cord 341 with the rear end of the releasing arm 338 and projecting with its rear end into the path of the cross bar 25, as represented in Figure 8.

The main number keys are held in their depressed position until the rocking frames 15 and 29 have been moved forwardly sufficiently to operate the registering and recording mechanisms in accordance with the numbers of the depressed main keys and then the cross bar 25, during the last part of its forward movement with the rocking frames 15 and 29 engages with the releasing lever 340 and depresses the same. The releasing arm 338, during its downward movement with the releasing lever 340 engages with the lower arm of the elbow lever 336 and turns the latter so that its upper arm moves the main releasing bar 333 toward the left and moves the main locking plates out of engagement with main number keys, thereby releasing the depressed main keys and permitting them to rise preparatory to setting the machine for registering and recording the next number.

The row of word keys 216 is arranged on the left-hand side of the main keys and the keys 401 of the auxiliary adding mechanism are arranged on the left hand side of the word keys. Each row of word and auxiliary number keys is provided with a locking mechanism similar to those of the rows of main keys.

The several shifting keys are arranged in a longitudinal row or column on the left side of the auxiliary keys, and the elbow levers operated thereby are arranged one behind the other as represented in Figures 8, 11 and 12.

342 represents an auxiliary releasing bar whereby the locking plates of the auxiliary keys are released. This bar is arranged transversely of the machine, in front of and parallel with the main releasing bar 333 and is adjustably connected therewith, so that the auxiliary releasing bar can be moved into an operative or inoperative position on the main releasing bar.

As shown in Figure 11, the auxiliary releasing bar is pivoted at its inner end to the main key releasing bar by a horizontal pivot through an opening 343 in the frame, as shown in Figure 15, which permits this bar to be manipulated by the operator from the outside of the frame. The auxiliary releasing bar is held in its raised or lowered position by means of two notches or recesses 344, 345, formed one above the other in this bar

and each of which is adapted to be engaged with a pin or projection 346 on the main releasing bar, as shown in Figures 11 and 15, by the resilience of the auxiliary releasing bar 5 which is sufficiently elastic for this purpose. Upon raising the auxiliary releasing bar and engaging its lower recess with the pin 346, the releasing lugs 347 of this bar are carried in front of the right side of the pins 10 on the rear ends of the locking plates of the auxiliary keys, so that upon moving the main releasing bar toward the left for releasing the main keys, the auxiliary releasing bar is simultaneously moved in the same 15 direction and disengages the locking plates from the auxiliar keys. When it is desired to register or record an arithmetical progression of a number the auxiliary releasing bar is depressed, so that its lugs 347 are below 20 the pins of the locking plates of the auxiliary keys, this bar being held in this position by engaging its upper recess 344 with the pin 346. Upon now depressing the auxiliary keys of the desired number and then operating 25 the registering and recording mechanism the number represented by the depressed keys will be registered and recorded, but these keys will not be released. While the depressed keys are thus held in a depressed 30 position, the registering and recording mechanism can be repeatedly operated, during each of which operations the number represented by the depressed key is added over and over again, thereby registering and recording 35 the arithmetical progression of this number.

The two columns or rows of word and shifting keys are each provided with a locking mechanism similar to the main and auxiliary 40 keys, but the locking plates of these keys are disengaged from the stems by a separate releasing mechanism so as to permit the main and auxiliary number keys to be released without releasing the word and shifting keys. 45 As shown in Figures 11 and 12, the release of the word and shifting keys is effected by a supplemental releasing bar 348 having lugs 349 which engage with the pins 335 on the rear ends of the locking plates of the word 50 and shifting keys and which is guided at its outer end in the frame. The inner end of the supplemental releasing bar is pivoted to the upper arm of a releasing elbow lever 350. This lever is pivoted on the pin 337 55 and its lower arm projects toward the right and underneath the releasing arm 338 adjacent to the rear side of the lower arm of the releasing elbow lever 336.

When both lever arms of the releasing elbow levers 336 and 350 are arranged underneath the releasing arm 338, the depression of the latter by the rocking frames causes the supplemental releasing bar to be moved toward the left so that its lugs disengage 60 the locking plates of the word and shifting

keys from their respective stems at the same time that the main and auxiliary releasing bars disengage the locking plates of the main and auxiliary number keys from their respective stems, thereby releasing all the keys simultaneously after the registering and recording of the words and numbers has been effected. 70

Repeat key

75

For the purpose of permitting all the words and numbers represented by the depressed keys to be added and recorded repeatedly, the releasing elbow levers 336, 350 are shifted toward the right and their lower arms are moved from underneath the releasing arm 338 so that the depression of the lever 340 by the rocking frames will not affect the releasing elbow levers 336, 350, thereby retaining the keys in their shifted position and permitting of producing repeated additions and impressions of the types which correspond to the depressed keys. The releasing elbow levers 336, 350, are moved into an operative or inoperative position by means of a supporting elbow lever 351 as shown in Figures 8, 11 and 12. This lever is pivoted on a stationary bracket 352 and its upper arm carries the pin 337 on which the releasing elbow levers 336, 350 are pivoted. 353 represents an actuating rock lever which engages with its rear arm against the underside of the lower arm of the supporting elbow lever 351. 80

354 (Figs. 8 and 14) represents a repeating shifting key having a depending stem which is guided in the top and bottom of the key-board and which engages with its lower end against the front arm of the actuating rock lever 353. Upon depressing the repeating key, the supporting elbow lever 351 is turned by the actuating lever in the direction for moving the releasing elbow levers 336, 350 so that their lower arms clear the releasing arm 338 and will not be affected by the depression of the latter. 90

Upon releasing the repeating key the supporting elbow lever 353 is returned to its normal position by a spring 355, shown in Figures 8 and 11, and the releasing elbow levers 336, 350 are shifted into an operative position 105 with their lower arms projecting underneath the releasing arm 338. The releasing elbow lever 350 is turned in the direction for moving the supplemental releasing bar 348 into its retracted position by a spring 356 which is secured to the supporting elbow lever 351. The movement of the elbow lever 350 in this direction is limited by a stop 357 on the supporting elbow lever 351, as shown in Figures 11 and 12. 115

When it is desired to record the totals of the added numbers or when it is desired to turn the dials to zero, the number keys must all be released in order to permit the key levers to assume a position corresponding to 120 125 130

the dials preparatory to recording the total registered by the same. This is effected by an intermediate elbow lever 358 which is pivoted on the pin 339 and which projects rearwardly over the lower arm of the releasing elbow lever 336 but does not project over the lower arm of the releasing elbow lever 350, as shown in Figures 11 and 12. 359 represents a longitudinal connecting bar connected at its rear end to the lower arm of the intermediate elbow lever 358 and provided with longitudinal slots 360 which receive pins or projections 361 on the lower arms of the elbow levers 80 and 85 which are operated by the total and zero keys 84 and 87, as represented in Figure 8. The pins 361 of the total and zero elbow levers engage normally with the front ends of their respective slots in the connecting bar 359 which causes the latter to be shifted forward by any one of the respective keys without disturbing the others. Upon moving the connecting bar 359 forwardly by the depression of any one of the total or zero keys, the intermediate elbow lever 358 is turned in the direction for depressing its upper arm into engagement with the lower arm of the releasing elbow lever 336, thereby releasing all of the number keys. The depressed word keys and the shifting keys remain depressed until the rocking frames 15 and 29 have completed their forward movement and the registering and recording of the totals have been effected. The locking mechanism of the shifting keys is so constructed that the zero key 87 cannot be held down by the adjacent locking plate, as shown in Figure 8, because the depression of the same is necessary only during the backward movement of the rocking frames.

As illustrated in the drawings and as completely described in the parent application Serial No. 1,004, now Patent No. 1,429,201, a key inter-locking mechanism is provided whereby not more than one key in each of the columns of word and number keys may be in fully operative position at any one time and whereby not more than a predetermined plurality of keys of the row of shifting keys may be in fully operative position at any one time; but as this specific mechanism forms no part of the invention hereby intended to be covered, it is not here described in detail; but is fully described and claimed in another pending divisional application Serial No. 249,905, filed August 14, 1918, now Patent No. 1,334,533, granted March 23, 1920, to which reference is hereby made.

I claim:

1. In a calculating machine comprising accumulating mechanism, printing mechanism, a total key for causing said printing mechanism to print a total according to the amount which has been accumulated upon said accumulating mechanism, in combination means for locking said total key in controlling po-

sition and means for automatically retaining said total key in controlling position during repeated actuations of said totaling and printing mechanisms.

2. In a calculating machine comprising a set of accumulators operable to accumulate items, printing mechanism operable for printing such items as they are accumulated, key mechanism for determining the items to be accumulated by said accumulators and printed by said printing mechanism, and operating mechanism for operating said accumulators and printing mechanism according to the control of said key mechanism, in combination, manipulative means co-operative with said operating mechanism for causing said printing mechanism to print the total amount standing on said accumulators, and means whereby said manipulative means may be set and left in such set position without further attention from the operator for controlling said printing mechanism to print the total accumulated on said set of accumulators at each of a plurality of successive operations of said operating mechanism.

3. In a calculating machine, the combination with an accumulator, recording mechanism for recording the items accumulated on said accumulator, setting key mechanism stationarily mounted on the framework of said machine, and whereby items may be set up to be accumulated by said accumulator and printed by said printing mechanism, repeating mechanism by the operation of which an item may be repeatedly accumulated into said accumulator with a single setting of said setting key mechanism and without further movement of said keys, mechanism whereby the operation of said recording mechanism may be discontinued during operation of said repeating mechanism, and means for causing said recording mechanism to print totals resulting from operation of said repeating mechanism.

4. In a key-controlled machine, the combination with mechanism to be controlled, of a plurality of settable keys for controlling said mechanism, operating mechanism for operating the first said mechanism according to the control of said keys, a repeat key for causing a single setting of said keys to effect the same control of the first said mechanism at each of a plurality of successive operations of said operating mechanism, and automatic means for positively preventing said repeat key from being moved out of operative position.

5. In a key-controlled machine, the combination with mechanism to be controlled, of a plurality of settable keys for controlling said mechanism, operating mechanism for operating the first said mechanism according to the control of said keys, a repeat key for causing a single setting of said keys to effect the same control of the first said mechanism at

- each of a plurality of successive operations of said operating mechanism, automatic means for locking said repeat key in operative position, and a key operable to release said repeat key from said automatic means.
5. The combination with the main registering mechanism and its controlling keys and the auxiliary registering mechanism and its controlling keys, of main and auxiliary locking devices whereby the keys of the main and auxiliary registering mechanisms may be held in an operative position, a main releasing device whereby the main locking device is disengaged from the main keys, an auxiliary releasing device whereby the auxiliary locking device is disengaged from the auxiliary keys and which is connected with the main releasing device, and means whereby the auxiliary releasing device may be shifted into an operative or inoperative position while remaining connected to the main releasing device, substantially as set forth.
6. The combination with the main registering mechanism and its controlling keys and the auxiliary registering mechanism and its controlling keys, of main and auxiliary locking devices whereby the keys of the main and auxiliary registering mechanisms may be held in an operative position, a main releasing device whereby the main locking device is disengaged from the main keys, an auxiliary releasing device whereby the auxiliary locking device is disengaged from the auxiliary keys and which is connected with the main releasing device, and means whereby the auxiliary releasing device may be shifted into an operative or inoperative position while remaining connected to the main releasing device, substantially as set forth.
7. In a calculating machine, the combination of a plurality of accumulators operable to accumulate items, a plurality of rows of depressible keys operable for determining the items to be accumulated by said accumulators, means for detaining any of said keys in depressed position when depressed, operating mechanism operable to effect accumulating by said accumulators according to the control of said keys and normally to effect release of any detained keys of said plurality of rows, and means whereby said operating mechanism may be rendered ineffective with relation to the return of the keys of certain of said rows of keys only, while remaining effective with relation to the return of the keys of other of said rows.
8. In a calculating machine, the combination of a plurality of accumulators; a plurality of rows of settable controlling keys for a corresponding plurality of said accumulators; means whereby when any of said keys is moved to controlling position, it automatically remains in controlling position; operating mechanism for operating said accumulators according to the control of said keys and for effecting the return to normal position of any of said keys which are in controlling position; and means whereby said operating mechanism may be rendered ineffective with relation to the returning of the keys of certain of said rows only while remaining effective with relation to the returning of the keys of other of said rows.
9. In a calculating machine, the combination of accumulating mechanism operable to accumulate items, a plurality of keys each of which is movable from normal ineffective position to effective position to remain in effective position when moved thereto for determining items to be accumulated by said accumulating mechanism, operating mechanism operable to cause said accumulating mechanism to accumulate items determined by said keys and for effecting return to normal position of any of said keys which may have been moved to effective position, and a plurality of optionally operable devices for rendering said operating mechanism ineffective with relation to the return of a plurality of said keys to normal position.
10. In a calculating machine, the combination of an accumulating mechanism, a plurality of settable devices which control the amount to be accumulated on said accumulating mechanism at an operation of said machine, means which may be set to cause any of said devices in set position to repeatedly effect the same control of said accumulating mechanism, and settable means for modifying the action of the first said means to cause certain of said devices exclusively to repeatedly effect the same control of said accumulating mechanism.
11. In a calculating machine, the combination of a plurality of sets of accumulators, the accumulators of each set being of successive denominational order, and a plurality of accumulators of one of said sets being of the same denominational orders as the corresponding accumulators of another of said sets of accumulators; key-controlled setting mechanism for controlling the items to be accumulated on a plurality of said sets of accumulators; a common operating mechanism for simultaneously operating all of said sets of accumulators according to the control of said setting mechanism; and common means for causing a single setting of said setting mechanism to control accumulators during a plurality of operations of said operating mechanism.
12. In a calculating machine, the combination of a plurality of sets of accumulators, the accumulators of each set being of successive denominational order, and a plurality of accumulators of one of said sets being of the same denominational orders as the corresponding accumulators of another of said sets of accumulators; a plurality of sets of setting-keys, one set for each of a plurality of said sets of accumulators, the keys of each being operable for controlling the items accumulated on the respective set of accumulators; common operating mechanism for simultaneously operating all of said sets of accumulators according to the control of their respective sets of keys; and means common to a plurality of said sets of keys for causing a single setting of the keys in any of such sets to control accumulations on the respective sets of accumulators during a plurality of operations of said operating mechanism.
13. The combination of a numeral-printing device, numeral keys for controlling said numeral printing device, a special key, a printing device comprising an element controllable by said special key for controlling

- printing of special matter other than numerals in conjunction with the numerals printed by said numeral printing device, an operating mechanism for operating both of said printing devices according to the control of their respective keys, a device for retaining said special printing device in controlled condition after said special key has been operated, mechanism for automatically releasing the 5 special printing device from the last said device, and a device for rendering the last said mechanism ineffective.
14. The combination of a plurality of sets of main printing types; a plurality of sets of auxiliary printing types; impression devices co-acting with said types and co-operatively inter-related so that operation of one of said impression devices may cause operation of another of said impression devices, such inter-relationship being interrupted between the 15 impression devices co-acting with the main printing types and the impression devices co-acting with the auxiliary types; a plurality of keys each movable from normal 20 to operative position for setting up the matter to be printed by said main printing types; a plurality of keys each movable from normal to operative position for setting up the matter to be printed by said auxiliary types; 25 a manipulative member, the operation of which renders a single setting of any of said keys operative during each of a plurality of operations; and an operating mechanism operable at a single operation to effect printing by said main and said auxiliary types according to the setting of the respective 30 pluralities of keys.
15. In a key mechanism, the combination of a plurality of controlling keys, each of said 40 keys being movable from normal to operative position; universal means for effecting return of said keys from operative to normal position; and means for rendering said universal means ineffective with relation to one of said 45 keys while said universal means remains effective with relation to another of said keys.
16. In a key mechanism, the combination of a plurality of settable keys, means for detaining any of said keys in set position when 50 set, means for releasing the detained keys from the detaining means, and means for rendering said releasing means ineffective with relation to one of said keys while said releasing means remains effective with relation to another of said keys.
17. In a key-controlled machine, the combination of a plurality of rows of controlling keys, each of said keys being movable from normal to operative position; means for effecting the return to normal of any of said 55 keys which may have been moved to operative position; and means for rendering the first said means ineffective with relation to one of said rows of keys while it remains effective with relation to another of said rows of keys.

18. In a key-controlled machine, the combination of a plurality of rows of controlling keys, means for detaining said keys in controlling position, means for causing said detaining means to release all of the keys detained thereby, and means for rendering the second said means ineffective with relation to one of said rows of keys while it remains effective with relation to another of said rows.

19. In a key mechanism, the combination of a plurality of groups of rows of keys, each of which keys may be moved from normal to operative position; a device for controlling restoring to normal position of any key which has been moved to operative position in one of said groups of rows of keys; a device for controlling restoring to normal position of any key which has been moved to operative position in another of said groups of rows of keys; universal operating mechanism for both of said devices; and means for rendering one of said devices ineffective while the other device remains effective.

20. In a key-controlled machine, the combination of a plurality of series of keys, each of said keys being movable from normal to operative position; means for effecting the return to normal of any of said keys which may have been moved to operative position; optionally operable means for rendering the first said means ineffective with relation to certain of said series of keys while it remains effective with relation to other of said series of keys; and means for rendering the first said means ineffective with relation to all of said series of keys.

21. In a calculating machine, a plurality of keys, a plurality of detents adapted to maintain the keys in their depressed position, a slide adapted to engage said detents, means for actuating said slide, an additional key, and means controlled thereby for disconnecting the slide from said actuating means.

22. In a calculating machine, the combination with operating means therefor, of a repeat key, a total key, and mechanism controlled by the total key which will cause the repeat key to be restored when a total is taken.

23. In a machine of the class described, the combination with a bank of keys and a key detent, of a hand operated lever, a bell crank lever pivoted thereon for actuating said detent, and a main operating mechanism, an element of which actuates said bell crank lever.

24. In a calculating machine, the combination with multiplying mechanism operable to multiply numbers, one by the other, of recording mechanism, a common operating means cooperating with said multiplying and recording mechanisms, means for preventing effective operation of the recording mechanism during multiplying operations, and means for causing said recording mechanism

to record the product resulting from operation of the multiplying mechanism.

25. In a calculating machine, the combination with multiplying mechanism including parts adjustable to represent numbers and wheels to receive products, of recording mechanism, a common operating mechanism for causing operation of said wheels and said recording mechanism, means for rendering said recording mechanism ineffective during multiplying operations, and means for causing said recording mechanism to record the product resulting from operation of the multiplying mechanism.

26. In a calculating machine, the combination with multiplying mechanism, including parts adjustable to represent numbers to be multiplied and wheels to receive products, of recording mechanism, a common operating mechanism for causing operation of said wheels and said recording mechanism, means for rendering said operating mechanism ineffective with respect to said recording mechanism during multiplying operations, means for causing said recording mechanism to record the products resulting from operation of the multiplying mechanism, and means for restoring to idle position the parts in the multiplying mechanism which had been adjusted to represent the number to be multiplied.

27. In a calculating machine, the combination with multiplying mechanism operable to multiply numbers, one by the other, of recording mechanism, a common operating mechanism cooperating with said multiplying and recording mechanisms whereby multiplying and recording may be effected concomitantly and means controllable by the operator for preventing effective operation of the recording mechanism during multiplying operations.

28. In combination, a set of accumulators, means to control the entry of amounts thereon, an indicating device, and means for operating said device, in conjunction with the entry of amounts differing from each other on said set of accumulators, to indicate a series of numbers in arithmetical progression which may have as its common difference a number other than unity or any power of ten.

29. In a calculating machine, the combination of a plurality of accumulators, members manually movable from normal to operative position for controlling accumulations on said accumulators, universal means for restoring said members from operative to normal position, and means for rendering said universal means ineffective with relation to one of said members while said universal means remains effective with relation to another of said members.

30. In a calculating machine, the combination with the main frame thereof; of a plu-

rality of accumulators; a keyboard comprising a plurality of rows of keys, one row for each of a plurality of said accumulators, said keyboard being secured to and supported by said main frame so as to be bodily immovable with relation thereto; a plurality of locking devices, one locking device for each row of a plurality of said rows of keys for locking in depressed position any key of the respective row when such key is depressed, and each of said devices being operable by the depression of any key of its respective row to release any previously depressed key of the same row; a universal operating mechanism for operating said accumulators to accumulate according to the control of their respective keys and for operating all of said devices to release all of said keys which may have been depressed; and means for rendering said universal mechanism ineffective with relation to said devices.

31. In a calculating machine, the combination of a plurality of accumulators; a plurality of rows of manually movable controlling members, one row for each of a plurality of said accumulators; means whereby when any of said members is moved to controlling position it automatically remains therein; mechanism for effecting return to normal position of any of said members which are in controlling position; and means whereby said mechanism may be rendered ineffective with relation to the returning of the members of one of said rows without being rendered ineffective with relation to the returning of the members of another of said rows.

32. In a calculating machine, the combination with type-carriers and hammers automatically released when the type-carriers operate, of multiplying devices and means for holding the hammers when said devices operate; substantially as described.

33. In a calculating machine, the combination of a plurality of sets of accumulators; a key mechanism for setting up items differing from each other to be accumulated on one of said sets of accumulators; and means whereby a digit greater than the lowest digit of a denominational order of another of said sets of accumulators may be automatically repeatedly entered into that order concomitantly with item-accumulating operations of the key-controlled set.

34. In a calculating machine, a plurality of accumulators; actuators therefor; a plurality of rows of keys for a corresponding plurality of said actuators; stops settable by depression of said keys for limiting movement of said actuators; a plurality of locking devices, one for each of a plurality of said rows of keys for locking in depressed position any key of the respective row when such key is depressed; a universal operating mechanism for causing said actuators to actuate

said accumulators according to the control of said stops and for operating all of said devices to release all of said keys which may have been depressed; and means for rendering said universal mechanism ineffective with relation to said devices.

35. In a calculating machine, the combination with the main frame thereof; of a plurality of accumulators; actuators for said accumulators; a keyboard comprising a plurality of rows of keys for a corresponding plurality of said actuators, said keyboard being secured to and supported by said main frame so as to be bodily immovable with relation thereto; stops settable by depression of said keys for limiting movement of said actuators; a plurality of locking devices, one for each of a plurality of said rows of keys for locking in depressed position any key of the respective row when such key is depressed; a universal operating mechanism for causing said actuators to actuate said accumulators according to the control of said stops and for operating all of said devices to release all of said keys which may have been depressed; and means for rendering said universal mechanism ineffective with relation to said devices.

36. In a calculating machine comprising a plurality of accumulators and a plurality of rows of settable keys associated respectively with said accumulators, the combination of a plurality of locking devices one for each of said rows of keys for holding the keys when set and each operable upon the depression of a second key in its row to release a previously depressed key in said row, a universal operating mechanism for operating said accumulators according to the control of their respective keys and for operating all of said locking devices to release any depressed key, and means for modifying the action of said operating device to render it ineffective upon the locking devices of certain of said rows of keys while it remains effective with respect to the locking devices for other rows of keys.

37. In a calculating machine comprising a plurality of sets of accumulators each including accumulators of like successive denominational orders, a set of settable number keys for each set of accumulators and associated therewith for controlling items accumulated thereon, and a universal operating mechanism for effecting accumulation on said accumulators under the control of their respective sets of keys and for returning any set keys to normal position; in combination, a printing mechanism controllable by the keys and operable by the operating mechanism to print the items accumulated, a total key mechanism cooperative with said operating mechanism for effecting printing of accumulated totals under the control of sets of accumulators and normally effecting the return to normal of any set number keys,

and means for rendering said total key mechanism incapable of thus restoring any set number keys to normal.

38. In a calculating machine comprising a plurality of sets of accumulators each including accumulators of successive like denominational orders, a set of settable number keys associated with each of said sets of accumulators for controlling the items accumulated thereon, universal operating mechanism for effecting accumulation on said accumulators under the control of their respective sets of keys and for restoring any set number keys to normal position, printing mechanism controllable by said keys and operable by said operating mechanism to effect printing of the items accumulated and a total key mechanism cooperative with said operating mechanism for causing said printing mechanism to print accumulated totals under the control of said sets of accumulators and operable to effect the return to normal of any set number keys; in combination, a repeat key operable to cause a single setting of said number keys to effect control of said accumulators and printing means during each of a plurality of operations of the operating mechanism, and means whereby operation of said repeat key renders the total key mechanism incapable of restoring any set numeral keys to normal position.

39. In a key system for controlling a plurality of mechanisms having an operating mechanism common to and for operating said mechanisms and a series of settable keys for each mechanism for controlling the actuation of its associated mechanism only during each of an unlimited number of successive actuations thereof; in combination, a universal device cooperative with said operating mechanism for effecting the return to normal position of any of said keys which may be set in effective position, and manipulative means for rendering said universal device ineffective.

40. In a key system for controlling a plurality of mechanisms having an operating mechanism common to and for operating said mechanisms and a series of settable keys for each mechanism for controlling the actuation of its associated mechanism only during each of a unlimited number of successive actuations thereof; in combination, a special key, and means whereby the operating mechanism automatically restores to normal position said special key and any of said settable keys which have been set, and manipulative means for rendering said operating mechanism ineffective with relation to the returning of said keys to normal position.

WILLIAM S. GÜBELMANN.
